United States Patent

Des. 240,613
Patented July 20, 1976

240,613

MATERIAL HAULING AND DUMPING VEHICLE

Richard L. Thomas, Billy M. Lewis, Francis A. Bartley,
Walter I. Myers, and Edgar R. Goodbary, Tulsa, Okla.,
assignors to Goodbary Engineering Co.

Filed Nov. 22, 1974, Ser. No. 526,315

Term of patent 14 years

Int. Cl. D12—08

U.S. Cl. D12—15

Fig. 2

Fig. 3

Fig. 4

Fig. 5

FIG. 1 is an elevational view of one side of a material hauling and dumping vehicle showing our new design;

FIG. 2 is an elevational view of the opposite side thereof;

FIG. 3 is a front elevational view thereof;

FIG. 4 is a rear elevational view thereof;

FIG. 5 is a top plan view thereof.

We claim:

The ornamental design for a material hauling and dumping vehicle, substantially as shown.
